UNITED STATES PATENT OFFICE

MARGARET SMITH LARSON, OF DENVER, COLORADO

DESIGN FOR A PENGUIN DOLL

Application filed October 10, 1931. Serial No. 41,356. Term of patent 14 years.

To all whom it may concern:

Be it known that I, MARGARET SMITH LARSON, a citizen of the United States of America, residing at the city and county of Denver, and State of Colorado, have invented a new, original, and ornamental Design for a Penguin Doll, of which the following is a specification.

The Figures 1, 2, and 3, are respectively a front view, a side perspective view, and a rear view of a penguin doll, showing my new design.

I claim:

The ornamental design for a penguin doll as shown.

In testimony whereof, I affix my signature.

MARGARET SMITH LARSON.
